UNITED STATES PATENT OFFICE.

GAETANO DI GIOVANNI, OF NEW YORK, N. Y., ASSIGNOR OF ONE-FOURTH TO SALVATORE ZITO AND ONE-FOURTH TO JAMES W. SAITTA, BOTH OF BROOKLYN, NEW YORK.

WINDOW-WASHER.

1,081,100.

Specification of Letters Patent.

Patented Dec. 9, 1913.

Application filed October 1, 1912. Serial No. 723,291.

To all whom it may concern:

Be it known that I, GAETANO DI GIOVANNI, a subject of the King of Italy, and a resident of the city of New York, borough of the Bronx, in the county and State of New York, have invented a new and Improved Window-Washer, of which the following is a full, clear, and exact description.

This invention relates to improvements in window washers, and has for an object to provide an improved structure which may be adjusted in position and then operated until the window to which it is connected has been thoroughly cleaned.

15 A further object of the invention is to provide a window washer adapted to operate on either side of the window and to properly move across the window upon a back and forth movement of manually operated cords.

In carrying out the objects of the invention, a supporting frame is provided consisting principally in an upright and a base. Connected with the upright at the upper 25 end is a window engaging member designed to hold the upper end of the frame correctly in position while the lower end is held in position by the base. A pair of cables is mounted on this upright designed to carry 30 a cleansing tool, as for instance a scrubbing brush of any desired structure, or a wiping mechanism. This cleansing tool of whatever structure, is moved in one direction by the cables mounted on the upright, and 35 moved in the opposite direction by a hand-operated cable extending to a position near the base. If desired, a spring-operated roller could be provided to which the cords or cables on one side of the tool could be 40 connected so that the rollers will cause the cleaning tool to move in one direction while the cleaning tool is manually moved or pulled in an opposite direction.

A practical embodiment of the invention 45 is represented in the accompanying drawings forming a part of this specification, in which similar characters of reference indicate corresponding parts in all the views.

Figure 1 is a section through a window 50 showing an embodiment of the invention applied thereto; Fig. 2 is a view similar to Fig. 1, except that the same shows the device applied to the upper window sash and carrying a drying tool; Fig. 3 is an enlarged 55 front view of an embodiment of the invention with the cleansing tool removed; Fig. 4 is an end view of a drying tool; Fig. 5 is a transverse section through a cleansing tool; Fig. 6 is a front view of a slightly modified form of the invention; Fig. 7 is a top plan view of part of the structure shown in Fig. 6; Fig. 8 is a sectional view through Fig. 7 approximately on the line 8-8; Fig. 9 is a sectional view through Fig. 6 on the line 9-9; Fig. 10 is a section through Fig. 6 on the line 10-10; Fig. 11 is a front view of a slightly modified form of the invention to that shown in Fig. 6; and Fig. 12 is a sectional view through Fig. 11 on the line 12-12.

Referring to the accompanying drawings by numerals, 1 indicates the upper glass of a window, and 2 the lower glass, these glasses being carried by suitable sashes 3 and 4, respectively. When it is desired to wash the window pane 2, the washer is arranged so that the upwardly extending member 5 of the double hooked member 5' will extend for preferably a short distance between the sashes 3 and 4. At the same time that the double hooked member 5' is substantially encircling the lower part of the sash 3, the base 6 rests against the bottom of the window frame and may be held in place by brads, if desired. When it is desired to wash or operate on the pane 1, the sash 3 is lowered as shown in Fig. 2, and the double hooked member 5' is reversed so that the outer portion 7 will fit over the upper edge of the frame 3 and the base 6 will engage the outer part of the window casing or sill.

The base 6 may be of any desired length and is provided with an opening so as to telescopically fit over the standard 8 which is held in position with respect to the base by a suitable clamping screw 9. The standard 8 at its upper end has rigidly secured thereto a supporting plate 10 which is provided with a removable adjusting bolt 10' and a double hook-shaped retaining member 10''. The double hook-shaped member 5' is adapted to rest on the plate 10 and is provided with a longitudinal slot 5'' for accommodating the members 10' and 10'' so as to permit a proper adjustment of the double hooked member 5' and also to permit the same to be removed and reversed or turned over so as to assume the position shown in Fig. 1 or the position shown in Fig. 11.

Fig. 2. Connected with the lower surface of the plate 10 are brackets 12 and 13 carrying pulleys 14 and 15, over which pass cables 16 and 17. The cables 16 and 17 are connected at one end by suitable eyelets 18 and 19, to a tool carrying cross bar 20. The cross bar 20 is provided with grooves 21 and 22, into which are placed the flanges 23 and 24 of the cleansing tool 25, and the flanges 23' and 24' of the drying tool 25', these tools of course being used at different times. The ends of the cables 16 and 17 opposite the ends connected to the bar 20, are passed beneath pulleys 26 and 27 and connected with a hand-operated member 28 designed to remain normally in the interior of the building. The pulleys 26 and 27 are supported by brackets 29 and 30 secured to the base 6 so that any adjustment of the base 6 will, of course, cause a corresponding adjustment of the pulleys. In arranging the cables 16 and 17 over the pulleys 26 and 27, the same are passed under the pulleys and from thence over a roller 31 carried by brackets 32 and 33. In addition to the cables 16 and 17, a third cable 34 is provided which is connected at 35 to the bar 20 and is then passed downwardly and under the roller 31 and to a point near the handle 28. By this construction and arrangement, whenever the handle 28 is pulled inwardly or away from the pulleys 26 and 27, the bar 20 will be elevated, and whenever the cable 34 is pulled, the bar 20 will be lowered positively. A back and forth movement of the cables in this manner will of course cause a back and forth movement of the bar 20 and the tool 25 or 25', if the same is in position on the bar.

40 The cleansing tool 25 is formed with a tank structure 36 designed to carry water or other cleansing fluid, which is inserted through a suitable opening 37 normally held closed by a suitable stopper. On the face 45 of the tank 36 is a distributing member 38, preferably formed of rubber and provided with a plurality of apertures 39 registering with suitable apertures in the face of the tank. It will be evident that the face member for distributing the water could be of 50 fabric, or other material, as it not only distributes the water, but causes a washing or scrubbing action in its back and forth movement. After the pane has been washed 55 to the desired extent, the cleansing tool 25 is removed and the drying tool 25' is placed on the bar 20. The member 25' is formed with a body portion 40 on which the members 23' and 24' are mounted. The body portion 60 40 carries a plurality of friction members 41 for rubbing dry the surface of the glass. However, other forms of drying members besides member 41 could be employed without departing from the spirit of the invention.

Referring to Figs. 6 to 10 inclusive, a slightly modified form of structure is shown in which the base 6' is formed in a slightly different manner to the base 6 and the cleaning tool is constructed somewhat different. Referring more in detail to these figures, the base 6' is provided with a plurality of grooves 42, in each of which is arranged a pulley 43. These pulleys are adapted to accommodate the cables 16, 17, 75 and 34, so that the same may act substantially in a similar manner to the way the cables act in the preferred form. However, in order to properly space the base 6' from the lower edge of the window sash, an adjustable substantially U-shaped plate 44 is provided, formed with apertures 45 and 46 which accommodate a clamping bolt 47, the clamping bolt 47 being adapted to clamp the plate 44 in any of its adjusted positions so as to hold the member 8 and the cleaning tool a certain distance from the pane of glass being cleaned. In order to provide a proper bearing for the ends of the member 44, substantially U-shaped plates 48 and 49 90 are secured in any desired manner to the base 6'.

In addition to the construction just described, the form of the invention shown in Fig. 6 is slightly different with respect to 95 the cleaning tool and the movable tool supporting bar 20'. The bar 20' is designed to slidably fit on the standard or guide 8 and freely reciprocate thereon so as to move the cleaning tool 50. The cleaning tool 50 is 100 provided with a body 51, and a facing 52, preferably of rubber, which may be covered, if desired, by a cloth covering 53 held in place by suitable spring clamping members 54. The body 51 is rigidly connected with supporting pins 55 and 56 which extend through suitable apertures formed in the bar 20'. A spring 57 surrounds each of the pins 55 and 56 and continually presses pins 58 and 59 against an annular shoulder on 110 the bar 20' for maintaining, or tending to maintain the cleaning tool 50 in an outer or extended position. By this construction and arrangement of springs and associated parts, the cleaning tool is continually resiliently pressed against a pane of glass so as to provide a proper yielding frictional contact.

In Figs. 11 and 12 a slightly modified form of the arrangement of the upper part 120 of the device is disclosed, in which a movable plate 60 is clamped in the plate 10 and the double hooked member 5'. The plate 60 is provided with a pair of depending arms 61 which are adapted to carry a roller 62 containing a spring 63. The spring 63 is secured at one end by any desired means to a shaft 64, and at the opposite end is secured to the roller 62 so as to continually tend to turn roller 62 in a certain direction. This 125 130

causes the cables 16', and 17' to be rolled or coiled around roller 62 unless the cables 34' are being manually pulled or operated. The cables 16' and 17' are connected in any desired manner to the cleaning tool 50 and the cables 34' are also secured in any desired manner to the cleaning tool 50 so that when the cables 34' are pulled downward the cleaning tool 50 will be moved downward 10 and the cables 16' and 17' unwound and the spring 63 wound or brought under tension. Upon releasing the cables 34' the spring 63 will cause the rotation of the roller 62 and consequently cause the cables 16' and 17' to be wound thereon. In this way the cleaning tool 50 may be moved back and forth by one hand only, while the construction shown in Figs. 1 to 5 inclusive requires the operation of both hands for causing a proper up and down or back and forth movement of the cleaning tool.

Having thus described my invention I claim as new and desire to secure by Letters Patent:

1. In a window washer of the class described, a scrubbing tool, a framework for guiding the scrubbing tool, means for giving the scrubbing tool a back and forth movement, means arranged at the upper end of the framework engaging the lower part of the upper sash of a window when the lower pane is being washed, and means for engaging the upper part of the upper sash of a window when the upper pane is being cleaned.

2. In a window washer of the class described, a frame, a base for the frame adapted to rest against the window casing when the device is in use, a pivotally mounted hook member adapted to fit over the upper part of a sash when the device is being operated upon the upper window pane, a reciprocating member mounted on said frame, a cleaning tool connected with said reciprocating member, a pair of pulleys supported by said frame near the upper end, a pair of pulleys supported by said base, a pair of cables connected at one end to said reciprocating member and extending therefrom over the pulleys at the upper end of said frame and from thence down and under the pulleys on said base, a roller arranged on said base adjacent said pulleys and beneath said pulleys, and a single cable connected at the lower edge of said reciprocating member arranged so as to pass beneath said roller to a point near the ends of said first mentioned cables

whereby upon a movement of said first mentioned cables said reciprocating member will be moved upwardly and upon a movement of said last mentioned cable said reciprocating member will be moved downwardly.

3. In a window washer of the class described, a guiding framework, a plate rigidly secured to the upper end of said guiding framework, a reversible double hooked member mounted on said plate and formed with a slot, clamping means extending through said plate and through said slot for adjustably clamping said double hooked member in place, said double hooked member being adapted to engage the sash of the window for holding the upper end of the guiding frame in place, a base connected with the lower end of the guiding frame for holding the same in place, a reciprocating cleaning tool mounted on said guiding frame, and means for causing said tool to move longitudinally of said guiding frame.

4. In a window washer of the class described, a guiding frame, means for connecting the upper end of the guiding frame to a window sash, a base slidably engaging said frame, said base being formed with an adjustable plate for spacing said frame from the window being cleaned, a cleaning tool slidably mounted on said frame, and means for causing a reciprocatory movement of said cleaning tool longitudinally of the guiding frame.

5. In a window washer of the class described, a guiding frame, a supporting member at the upper end of the guiding frame for holding the upper end of the guiding frame in proper position adjacent a window, a base connected with said guiding frame, means for holding the base a predetermined distance from the window being cleaned, a reciprocating tool slidably mounted on said guiding frame, said reciprocating tool comprising a body, a cleaning member, means for holding the cleaning member on the body, a support, and resilient means for acting on the support for resiliently holding said body in a predetermined position, and means for causing a proper reciprocatory movement of said cleaning tool.

In testimony whereof I have signed my name to this specification in the presence of two subscribing witnesses.

GAETANO DI GIOVANNI.
